(57) **CLAIM**

The ornamental design for a wireless data repeater, as shown
and described.

DESCRIPTION

FIG. 1 is a top front perspective view of a wireless data
repeater showing our new design;

FIG. 2 is a front elevational view thereof;

FIG. 3 is a rear elevational view thereof;

FIG. 4 is a left side elevational view thereof, the right side
being a mirror image thereof;

FIG. 5 is a top plan view thereof; and,

FIG. 6 is a bottom plan view thereof.
